UNITED STATES PATENT OFFICE.

BENAIAH FARNUM, OF KEOKUK, IOWA.

REFRIGERATOR.

SPECIFICATION forming part of Letters Patent No. 241,853, dated May 24, 1881.

Application filed May 29, 1876.

To all whom it may concern:

Be it known that I, BENAIAH FARNUM, of Keokuk, Lee county, Iowa, have invented a new and useful Improvement in Refrigerators.

5 It is made substantially as set forth hereinafter, referring to the accompanying drawing, in which the figure is a vertical section of the refrigerator.

This invention relates to refrigerators for cooling and preserving food and other articles. The invention consists in forming the walls, each side, top, bottom, and end separate, with suitable arrangements for connecting them and taking them apart, in providing the refrigerator with a forcible circulation of the air for cooling it and the contents, and in various details of the apparatus.

The walls A are made hollow, of wood or other material, with air-spaces B between the 20 inner and outer shells. These spaces in the back and front sides are closed all around. In the two sides, C D, and the top and bottom E F these spaces connect, so as to pass entirely 25 around the center space or chamber, G, having the lateral edges closed. The six flat walls are made separate. Their edges are made to fit closely by being slightly concave. Into the joints a packing-strip of flannel, a cord, or other material, is put onto one part to make the 30 joint secure and close irregularities. The bottom F has curtain-edges and supports and a raised edge to set the upright sides inside of. The side walls, front, and back are set onto the bottom, inside the raised edge. The front 35 and back overlap the sides, and are secured to them solidly by heavy screws or screw-bolts at H H. The top E overlaps all the upright parts. The top and bottom are secured by screws, but may be used without. The front 40 has a large door, and in that a smaller door, for use as required. Racks are placed on the side walls. On these are mounted suitable sliding racks, K, which are drawn forward or pushed back, as desired; or shelves may be 45 used instead to hold the articles required.

The ice is placed in box L, which rests in bearings in the top of chamber G, so as to slide in and out. This has a rack-bottom to

hold the ice suspended, and a trough-bottom to convey off the water, which discharges by 50 a pipe at the back. Between the rack and bottom are openings in the sides to let a stream of air pass down through the ice.

The fan M is mounted on one side of the refrigerator, and turns by friction or other gearing, operated by hand, spring, or other power. This fan is connected with chamber G by passage N, so that a stream of air can be drawn out by the fan, and connects with the space B by passage N', so as to force the stream around 55 this passage and through the ice-box L at the top by downward opening P, so as to cool the air and the contents of the refrigerator by the circulation.

The refrigerator can be ventilated by forcing a stream of air by the fan out by passage B and outer opening, R, drawing in by opening S. These openings have stop-covers, which can be put on and secured in place. When thus ventilating the cover is taken from 60 70 passages R S and it is put into the opening R, as shown by dotted lines, so as to turn the air outward and stop it downward.

I claim—

1. A refrigerator having its outside walls in 75 sections removable to pack in smaller space for shipping, and with joints and passages so arranged as to fit together and to form air-passages within the walls from one section to another, substantially as set forth.

2. In a refrigerator, the combination of ice-chamber L, refrigerating-chamber G, air-forcing apparatus M, air-passages N, and outside walls formed in flat separable sections, arranged substantially as set forth.

3. In a refrigerator, the combination of several flat sections, made each separable from the others, and with edge joints and bearings, arranged to fit together and form the several sides of a refrigerator air-tight, substantially 85 90 as set forth.

BENAIAH FARNUM.
